Inventor.

James R. Taylor

United States Patent Office.

JAMES R. TAYLOR, OF NEW YORK, N. Y.

Letters Patent No. 60,966, dated January 1, 1867.

IMPROVED BOAT-DETACHING TACKLE.

The Schedule referred to in these Letters Patent and making part of the same.

TO ALL WHOM IT MAY CONCERN:

Be it known that I, JAMES R. TAYLOR, of the city, county, and State of New York, have invented certain new and useful improvements in Apparatus for Detaching Boats; and I do hereby declare the following to be a full, clear, and exact description of the same, reference being had to the accompanying drawings, making a part of this specification, in which—

Figure 1 represents a sectional elevation of the apparatus as attached to a boat.

Figure 2 represents a vertical section of the apparatus as it would appear when disconnected from the boat; and

Figure 3 represents a top plan of the bow of a boat with the detaching apparatus in place.

The object and purpose of my invention are to launch a life or other boat in a heavy sea by means of an apparatus connected to and operated from the boat, and with safety to the crew. And my invention consists in combining with the hinged hooks by which the boat is suspended a reinforce or secondary hook, which takes into a mortise in the strap-frame, and relieves the pivot of the hinge of the main hook from much of the strain upon it. And in connection with the trip, for allowing the main hook to open, my invention consists in giving it such a form that, after it has been swung partially away from the hook, the latter will aid in throwing it out, and thus relieving itself quickly and with certainty.

To enable those skilled in the art to make and use my invention, I will proceed to describe the same with reference to the drawings.

At the bow of the boat, and to the stem-post A, or otherwise, I fasten a head-piece, B, which has straps, c, running down the stem-post and securely fastened to it. To this head-piece, B, is pivoted a hook, D, which, when down, passes into a seat, a, in a projection, E, which may be a part of the head-piece B. In this position a cam or eccentric lever, F, is swung around against the hook, and locks it in that position. On the hook D, beyond its pivoted point c, (as shown more distinctly in fig 2,) there is a reinforce or secondary hook, e, which, as the hook is let or shut down, takes into a mortise in the head, and holds under a solid portion of it, thus relieving the pivot of much of the weight of the boat, crew, and stores. Indeed, the pivot might give way entirely, and yet the hook could not yield or fly. The disconnecting lever or trip F is pivoted at f, and its long end, g, has a cord or chain, h, connected to it, by which it may be operated. The short end, i, of the lever is rounded off eccentrically, so that after it is started from its locking position against the hook, the tendency of the hook to fly or raise up will aid in throwing out said locking lever, and thus facilitate the operation of detaching the boat from the tackle by which it is let down. A duplicate apparatus may be arranged at the stern of the boat, so that a single person, by drawing upon the cords or chains connected with each, may let the boat go by the bow and stern simultaneously, or by the stern first and then by the bow, as may be most desirable in view of the state of the sea in which she is launched. Instead of the lever F working horizontally it may work vertically, it being only necessary to cut a vertical mortise through the timber G, on which it is pivoted, to effect this modification of it.

What I claim as my invention, and desire to secure by Letters Patent, is—

In combination with a hook used in a boat-detaching apparatus, a reinforce or secondary hook e, which catches under a solid portion of the head, and thus relieves the pivot of the hook, or makes a safety connection should the pivot of the hook give way, substantially as described.

And I claim, in combination with the hook and its reinforce, an eccentrically-formed tripping-lever, that is aided in being tripped or removed by the pressure of the hook upon its curved edge, substantially as described.

JAMES R. TAYLOR.
